UNITED STATES PATENT OFFICE

AMAN MOORE, OF PORTLAND, COLORADO.

PROCESS FOR THE UTILIZATION OF PULVERULENT FUEL.

No. 820,236.

Specification of Letters Patent.

Patented May 8, 1906.

Application filed July 12, 1905. Serial No. 269,404.

To all whom it may concern:

Be it known that I, AMAN MOORE, a citizen of the United States of America, residing at Portland, county of Fremont, State of Colorado, have invented certain new and useful Improvements in Processes for the Utilization of Pulverulent Fuel, of which the following is a specification.

My invention relates to a process for the utilization of combustible material in pulverulent form as a fuel. In certain of the arts the employment of fuel in pulverulent form is essential, particularly, by way of illustration, in the manufacture of hydraulic cement. It is, moreover, essential in cement manufacture, as in other arts in which pulverulent fuel is used, to provide for the supply along with the fuel of a combustion-supporting fluid, such as air or steam, in sufficient volume to promote practically instantaneous and perfect combustion of every particle of the fuel.

It has been the practice to discharge the fuel with its combustion-supporting fluid into a combustion-chamber or furnace, where the heat required of it is generated in such manner and under such conditions as are imposed by the art in which the fuel aforesaid is used.

My present invention, relating to a process for promoting the combustion of pulverulent fuel, has for its essential object means of distributing the fuel with and preferably by the aid of a combustion-supporting fluid within the combustion-chamber in such manner and under such conditions as may most perfectly secure the object sought to be obtained—namely, perfect, instantaneous, and uninterrupted combustion of the fuel-supply.

The preferred apparatus for carrying my process into effect I describe in my companion application filed herewith, Serial No. 269,403, to which reference is hereby made.

The apparatus aforesaid is shown in the accompanying drawings and described in the following specification.

What constitutes my invention will be hereinafter specified in detail and succinctly set forth in the appended claims.

Referring to the drawings which accompany and constitute a part of this specification, Figure I is a side elevation of that which for convenience of designation I denominate my "atomizer," showing diagrammatically its application to a combustion-chamber. Fig. II is a longitudinal vertical

section of the atomizer. Fig. III is an elevation of the discharge end of the atomizer. Fig. IV is a similar view of the opposite end thereof. Fig. V is a transverse vertical section of Fig. I, showing the internal construction of one form of the barrel of the atomizer in section. Fig. VI is a view similar to Fig. V, showing a modification of the barrel construction. Fig. VII is a vertical section of the barrel of the atomizer detached and showing diagrammatically a flame projected across and to the opposite side of a diagrammatically-indicated combustion-chamber. In this figure equilibrium of pressure in the several pressure-chambers adapted for the supply of an oxygenous fluid is indicated by three arrows above and an equal number below. Fig. VIII is a view similar to Fig. VII, illustrating diagrammatically distribution of fuel with and by the aid of its oxygenous envelop to the medial portion and to one side of the diagrammatically-indicated combustion-chamber. Preponderance of pressure in one pressure-chamber over that in the opposite chamber is indicated by two arrows above and four arrows below. Fig. IX is a view similar to Fig. VII, illustrating fuel distribution to the side of the combustion-chamber opposite the side to which it is shown as distributed in Fig. VIII. Preponderance of pressure in the pressure-chamber is shown by four arrows above against two arrows below.

Referring to the numerals on the drawings, 1 indicates the outer wall, 2 the inner wall, and 3 the end wall, which, combined with an end plate 4, constitute that which I designate as the "barrel" of my atomizer in the preferred form of embodiment of my apparatus illustrated. The walls 1 and 2 are preferably coaxial cylinders united by an integral end wall 3, while the plate 4 is preferably an annulus of a width sufficient to extend flush with the walls 2 and 3, against and opposite the ends of which it is secured in such manner as to effect a close joint between the parts.

The inner wall 2 of the barrel surrounds and with the plate 4 defines the center bore of my atomizer, through which, as by a blast of air or through ordinary or suitable means common in the art or arts to which my invention is adapted, as has been specified, fuel in pulverulent or equivalent form is forced in the quantity desired, determinable by the temperature required to be generated in the furnace 40. No other means than the center

bore for the fuel discharge are illustrated, because the means contemplated are well known in the art and do not in themselves constitute any part of my present invention.

5 The walls 1 and 2, spaced and united by the integral wall 3 and the plate 4, define between them a space for the reception of an oxygenous fluid—such, for example, as air or steam—which being discharged about the 10 blast through the center bore constitutes an oxygenous or combustion-supporting envelop about the fuel-supply. I prefer to provide as a means of discharge of the contents of said space and for the formation of the oxygenous envelop an annular or substantially annular series of equidistant orifices or drill-holes 6, (see Fig. III,) preferably arranged to discharge under equal determinate pressure toward a definite focal point—such, for 15 instance, as that indicated by the reference-numeral 7 in Fig. VII of the drawings. The series of orifices 6 are preferably drilled through the wall 3.

It is the principal object of my invention, 20 as has been specified, to provide for the distribution of the fuel as supplied through my atomizer to any point within the furnace or combustion-chamber. (Diagrammatically indicated in Figs. VII to IX, inclusive, of the 25 drawings, by the ellipse 8.) Having postulated that the point of fuel-supply is subject without limitation to the will of the operator, it may be specified that such distribution may be regarded, in effect, as a shifting of the 30 focal point from the conventionally-determined normal focal point 7 to any other focal point desired. Accordingly I have indicated in Figs. VIII and IX by way of illustration two other focal points 10 and 11.

35 The barrel being installed in practice in fixed relationship to the furnace which it supplies, the means of distribution or shifting of the focal point which I employ and which constitute an important feature of my invention consist of means for producing an inherently dirigible current, preferably an envelop which is constituted, as specified, of an oxygenous fluid. By an "inherently dirigible current" I mean one in which fluid means 40 forming part of the current itself are alone used to change the direction of the current.

The dirigibility of the envelop, by whatever means obtainable, characterizes the principle of my invention. In respect to the 45 apparatus the preferred means employed consists of a division of the space between the walls 1 and 2 into a plurality of chambers definable by longitudinally-disposed septa 12, extending between the walls 1 and 2 50 and which are preferably cast integrally with them. The number of septa is determinable by the number of chambers employed, which may be varied as preferred. For the purpose of this specification I show in Fig. V 55 four septa defining for separate chambers 14,

15, 16, and 17, and in Fig. VI, I show three septa 12, defining three separate chambers 19, 20, and 21.

The septa afford convenient means for securing the annular plate 4 to the barrel, which is shown in Fig. IV, provided with screw-holes 22, disposed with reference to the septa with which the barrel is provided, four screw-holes being shown in said figure to correspond with the four septa illustrated wherever they appear, save in Fig. VI of the drawings. Into these screw-holes are passed and screwed into threaded apertures provided for them in the several septa screws 24. (Indicated by dotted lines in Fig. II of the drawings.)

80 Each of the fluid-supply chambers 14, 15, 16, and 17, for example, is provided with an independently-controllable source of fluid-supply, represented in Figs. I and II of the drawings by pipes 25, 26, 27, and 28, each threaded into a nipple 29, provided for it preferably in the plate 4. (Compare Figs. I and II and IV.) 30, 31, 32, and 33 indicate valves with which the pipes aforesaid are respectively provided and which afford independent means for control of the pressure and volume of the fluid which passes through them.

85 The fluid-pressure within the several chambers may vary from a few ounces to a pressure, it may be, of hundreds of pounds. If the pressure be heavy and a large volume of combustion-supporting fluid be passed under equal pressure into the several chambers and discharged therefrom, it will produce a 90 quicker combustion and shorter flame than if no fluid or only a small volume of fluid or fluid at low pressure were discharged through the atomizer. It is therefore possible by variation of equal pressures in the several 95 chambers to shift the focal point from the position 7 (indicated in Fig. VII of the drawings) to any position desired along the axis of abscissas 35. If, on the other hand, the pressure in one or more of the chambers be 100 augmented beyond that in the other chamber or chambers, the focal point may be shifted not only as specified with reference to the line of the axis of abscissas 35, but also to any point of departure therefrom—such, for 105 example, as to points 10 and 11, (see Figs. VIII and IX,) indicated, respectively, upon the axis of ordinates 36. It is therefore obvious that by variation of pressure and of the 110 ratio of pressure in the several chambers 115 any point within the combustion-chamber without reference to its shape, but indicated diagrammatically in Figs. VIII to IX, inclusive, of the drawings by the ellipse 8 may be reached as a focal point.

120 It may be observed that by reason of the convergent disposition of the discharge-orifices 6 around the center bore of the atomizer the current of discharge of the combustion-supporting fluid is made athwart that of the 125 130

fuel discharge. It having been specified that the fuel-supply is preferably a dust-laden air-blast and that the oxygenous envelop is preferably a blast of air or steam, it will therefore be obvious to one skilled in the art that the conflict of the two currents tends not only to an intimate commingling of an oxygenous fluid with the fuel to be ignited, but also to the preservation of the pulverulent character of the fuel, in which state each separate particle of it being then most accessible to the combustion-supporting fluid which penetrates the mass is presented in the condition most favorable to its quick and complete combustion.

15 What I claim is—

1. A process for the utilization of fuel in pulverulent form which consists in discharging such fuel into a combustion-chamber along with a combustion-supporting fluid, and in distributing the same by means of a dirigible fluid-current to any point within the combustion-chamber desired.

2. A process for the utilization of fuel in pulverulent form which consists in distributively discharging such fuel into a combustion-chamber along with and by the aid of an inherently dirigible current of combustion-supporting fluid.

25 3. A process for the utilization of fuel in

pulverulent form which consists in distributively discharging such fuel into a combustion-chamber along with and by the aid of a dirigible combustion-supporting envelop.

4. A process for the utilization of fuel in 35 pulverulent form which consists in distributively discharging such fuel into a combustion-chamber along with and by the aid of a dirigible envelop constituted of an oxygenous fluid.

40 5. A process for the utilization of fuel in pulverulent form which consists in the discharge thereof along with and by the aid of an envelop of oxygenous fluid to a focal point within a combustion-chamber variable at the 45 will of the operator.

6. A process for the utilization of fuel in pulverulent form which consists in discharging the fuel into a combustion-chamber by a plurality of fuel-impelling fluid-currents the 50 ratio of pressures of the several currents being variable.

In testimony whereof I have hereunto signed my name in the presence of two subscribing witnesses.

AMAN MOORE.
